H. LANE,
ANIMAL TRAP.
FILED NOV. 5, 1920.

1,441,985.

Inventor -
Henry Lane,
By - B. Singer, Atty.

UNITED STATES PATENT OFFICE.

HENRY LANE, OF WEDNESFIELD, ENGLAND.

ANIMAL TRAP.

Application filed November 5, 1920. Serial No. 421,964.

To all whom it may concern:

Be it known that I, HENRY LANE, a subject of the King of Great Britain, residing at Eagle Works, Wednesfield, in the county 5 of Stafford, England, have invented certain new and useful Improvements in Animal Traps (for which I have filed applications in Great Britain, No. 144,553, dated November 7, 1919, and in Australia, Serial No. 10 14,251, filed February 4, 1920); and I do hereby declare that the following is a full, clear, and exact description of the same.

My invention comprises improvements in animal traps and refers to that class which 15 employ a spring either of wire or strip metal and a sheet metal base, the object of the present invention being to more rigidly secure the extremities of the wire or strip to the base in an improved, simpler and stronger manner and to provide general improvements in such traps.

According to this invention I press out a tongue piece from the base member to provide an opening through which one end of the 25 spring is passed, the said bent tongue portion being afterwards bent back into its normal position so as to engage the end of the spring whereby the latter is secured firmly to the base member.

30 The platform bearing surface for the treadle and the retaining notch for the pawl are all formed from one piece of sheet metal, the bearing surface for the treadle being of channel section, the two opposite flanges of 35 which are disposed substantially vertically and project below the platform, the said flanges being connected to the platform by web portions. The pawl is mounted on a bridge piece extending across the bifurcated 40 curled or bent over end of a transverse member secured to the base. The transverse member is secured by means of tongue pieces or pieces pressed out thereof and passing through holes in the base member, being 45 riveted over on the other side.

Referring to the drawings:—

Figure 1 is a perspective view of a base member with a wire spring in place ready to be fixed.

50 Figure 2 is a similar view of the finished trap.

Figure 3 is a similar view to Figure 2 but showing a strip spring.

Figure 4 is a section at 4—4 in Figure 1.

Figure 5 is a section at 5—5 in Figure 3. 55

Figure 6 is a perspective view of the platform of the trap.

Figure 7 is a similar view of retaining pawl.

Figure 8 illustrates the means for pivotally securing the pawl. 60

Figure 9 is a section through the transverse platform supporting member.

In carrying my invention into practice as 65 illustrated upon the accompanying drawings at Figures 1, 2 and 4 the base member 1 and the wire spring 2 are of the usual shape, the base member having its two extremities 3 bent up at right angles and the wire being coiled up in the middle, and having one end 70 4 adapted to be secured to the base member while the other end 5 forms a loop which engages with the jaws 6 of the trap in the well known manner.

One of the upright ends 3 of the base 75 member has a square tongue portion 8 bent out of it as seen in Figure 1, the metal being split along three lines to enable this to be done, the portion being bent along the fourth line of the square. This provides a hole 80 through which the ends of the springs can be passed. The extremities of the spring are preferably bent down so that when the spring is in position these pass through holes 10 in the base plate being riveted over on their 85 under sides. The portion 8 is now bent back into its normal position as shown in Figure 2 whereby the ends of the spring will be gripped between this portion and the main part of the base. 90

If desired and as illustrated notches 14 may be provided adjacent the two lower corners of the bent out portions into which the two parts of the spring may fit, the holes being of smaller diameter than that of the 95 wire so that it will be gripped by the bent out portion.

In Figure 3 the application to a strip metal spring is illustrated, the part 8 here again being bent up to allow the end 12 of 100 reduced width to be passed through, the extremity of the latter being bent down to pass through a slot 13 in the base member, the portion 8 being bent down as before to fix the spring. 105

The base member has a transverse member 15 of well-known form, as shown clearly in Figure 2, being secured to the base mem-

ber by the tongue pieces 16, 17 which are pressed out of the said member and pass through holes in the base member being riveted over on the under side as shown in Figure 9.

Adjacent one end of the said transverse member an upwardly extending lug 18 is secured by riveting or otherwise, this lug being the pivot member for the platform.

10 The platform 19 shown in Figures 2 and 6 is made of sheet metal and has its one side bent to provide two vertical walls 20, 21 adapted to fit around the aforementioned lug to which it is secured by a pin or the like

15 22 passing through holes 23, in the vertical walls and a hole 25 in the lug. The platform is also provided with a notch 26 adjacent the pivot to receive the nose of the pawl to be hereinafter explained.

20 The end of the transverse member extends upwardly at right angles to the main part as shown at 28 and the extremity is bent over upon itself at 29. A slot 30 is cut in this end member leaving a bridge portion 31 on the

25 end of the bent over part as clearly shown in Figure 8. This bridge portion serves as a pivot for the pawl 33 which as shown in Figure 7 is formed from a single piece of sheet metal having an extension 34 of reduced width, which is bent around the bridge portion 31 to pivotally secure it.

To set the trap the looped end of the spring is depressed out of engagement with the jaws of the trap, the jaws then being 35 opened to an approximately horizontal position, one of them being maintained in such position against the action of the spring by the engagement thereover of the pawl 33 which latter is then engaged in the notch 26 40 of the platform 19.

It will be apparent that when the weight of an animal acts upon the platform, it will be depressed, so that the pawl 33 is released, whereby the spring is freed to close the 45 jaws.

Claims:—

1. An animal trap comprising a sheet metal base member, a pair of jaws pivoted to said base, means for retaining said jaws in an open position, said means being releasable by the weight of an animal, a spring tending to close said jaws, one end of said spring passing through an opening in the base member, and a partially severed tongue on said base which engages with the end of the spring and serves to grip it between this portion and the main part of the base member.

2. An animal trap comprising a sheet metal base member, a pair of jaws pivoted to said base, means for retaining said jaws in an open position, said means being releasable by the weight of an animal, a wire spring tending to close said jaws, one end of said spring passing through an opening in the base member, a partially severed tongue on said base which engages with the end of the spring and serves to grip it between this portion and the main part of the base member, and notches in the end of said tongue adapted to fit around the said spring.

3. An animal trap comprising a sheet metal base, a pair of jaws pivoted to said base, a spring tending to close said jaws, means for retaining said jaws in open position, said retaining means being releasable by the weight of an animal and including a pivoted pawl and a platform pivoted to a vertical lug, said platform being pressed from sheet metal with an integral downwardly projecting flange the central portion of which is pressed outwardly to form a curved nose of channel section forming a hollow pivot lug adapted to fit over said vertical lug, and the curved edge of said nose being notched to receive the free end of said pawl.

In witness whereof I affix my signature.

HENRY LANE.
